L. M. Dehart.
Paddle Wheel.

No 12,621.

Patented Apr. 3, 1855.

UNITED STATES PATENT OFFICE.

LEVI M. DEHART, OF READING, PENNSYLVANIA.

ADJUSTABLE PADDLE-WHEEL.

Specification of Letters Patent No. 12,621, dated April 3, 1855.

To all whom it may concern:

Be it known that I, LEVI M. DEHART, of Reading, in the county of Berks and State of Pennsylvania, have invented certain new and useful Improvements in Adjustable Paddle-Wheels; and I do hereby declare the following to be a full, clear, and exact description of the same, reference being had to the accompanying drawing, representing a 10 side view of the wheel, with the interior parts represented in red lines.

The nature of my invention consists in providing hollow arms, which are permanently fixed to, or a part of, the hub, into 15 which hollow arms are passed other arms which carry sections of two, three, or more floats or buckets. The fixed arms being provided with a spur wheel, and the movable arms with a rack, so that the latter 20 arms with their buckets, may be drawn into, or run out of the hollow arms, for the purpose of diminishing or increasing the diameter of the wheel at pleasure.

To enable others skilled in the art to 25 make and use my invention, I will proceed to describe the same, first stating that, I am aware several plans of making reefing buckets have been essayed, but mine differs from this class of wheels, inasmuch as by 30 drawing in the buckets toward the center, the arms still project, and the circumference of the buckets only, and not the arms, is, or can be, diminished by such plan. I am also aware that an expanding propeller has been 35 devised, in which, as is described, though imperfectly shown, wings that expand like a telescope, or open like shutters, and these wings are run in and out by a rack and pinion at or near the shaft. This plan differs 40 from mine as paddle wheels generally differ from propellers, and the only thing common to both may be said to consist in the rack and pinion, to which I lay no 45 claim whatever, as it is described as one of the ordinary efficient means of moving or sliding one arm within the other, any other means of effecting the object may be as readily used.

The hub A, and the stationary hollow 50 arms B, may be cast in one solid piece, or the arms B, may be secured in any permanent manner to the hub A. I propose however to cast the hub and arms B, in two sections, divided centrally at right angles to 55 the shaft or axis of the wheel. This will admit of the interior of the hollow arms being planed out, so that the sliding arms may

fit snugly therein. An enlargement C, is left at or near the end of the arms B, in which is arranged a spur wheel or pinion D, 60 the axis of each of which may pass through the said arms to receive a crank or wrench F, by which they may be turned. These spur wheels, being inclosed within the arms, are beyond the reach of injury. 65

E, are arms fitting within the hollow arms B, and are provided with a rack, into which the pinion D, takes, and by means of the winch F, the arms E, may be run in and out at pleasure. The extreme outer 70 ends of the arms E, may terminate in two, three, or more branches G, on each one of which is a bucket H. By arranging the buckets in sections on the arms, it expedites their adjustment, as several may be thus 75 moved at one time. When the arms E, are run in or out to a suitable or desirable distance, they are held in adjustment by a set screw, pin, or bolt, or any other well known contrivance. 80

If found necessary to brace the buckets, each of the series may be united by a metallic segmental brace J.

The arms, buckets, &c., indeed, the entire wheel, may be increased or diminished in 85 number, or diameter, as experience, or the special purpose to which they are to be applied may require. But I have shown the general character of the construction of the wheel wherein the arms move with the 90 buckets, and not the buckets independent of the arms, as in the ordinary reefing wheels.

Having thus fully described the nature of my invention, I would state that, I am aware that reefing buckets on paddle wheels have 95 been used, and that an expanding propeller has also been essayed, in which the wings have been drawn toward the center, or run out, by means of racks and pinions, these I do not claim, but 100

What I do claim as new and desire to secure by Letters Patent is—

In combination with the hollow arms permanently fixed to the hub, the arms carrying the sections of the buckets, when said 105 arms are so arranged as to be slid within the hollow arms by a rack and pinion or its equivalent, substantially in the manner, and for the purpose herein set forth.

LEVI M. DEHART.
